(57) **CLAIM**

The ornamental design for a bottle filler station, as shown and described.

DESCRIPTION

FIG. 1 is a front left perspective view of a bottle filler fountain;

FIG. 2 is a front top perspective view thereof;

FIG. 3 is a front view thereof;

FIG. 4 is left side view thereof;

FIG. 5 is a top plan view thereof; and,

FIG. 6 is a bottom plan view thereof.

The broken line showing the environment in the drawings is for illustrative purposes only and forms no part of the claimed design.
